(57) **CLAIM**

The ornamental design for a canopy pole, as shown and described.

DESCRIPTION

FIG. 1 is a perspective view of a canopy pole showing the claimed design;

FIG. 2 is another perspective view of a canopy pole showing the claimed design;

FIG. 3 is a front elevational view thereof;

FIG. 4 is a top plan view thereof;

FIG. 5 is a bottom plan view thereof;

FIG. 6 is a partial enlarged view of an area labeled 6 in FIG. 1;

FIG. 7 is the second enlarged view of an area labeled 7 in FIG. 2; and,

FIG. 8 is the third enlarged view of an area labeled 8 in FIG. 2.

The broken lines illustrate portions of the canopy pole that form no part of the claimed design.

The dash-dot broken lines in FIGS. 1, 2 and 6-8 are included to show enlarged partial views. All other broken lines represent portions of the canopy pole that form no part of the claimed design. None of the broken lines form a part of the claim.
